SEALED PACKAGE

Louis A. Van Till, Brooklyn, N. Y., assignor to
 Anchor Cap & Closure Corporation, New York,
 N. Y., a corporation of New York

Application July 18, 1930, Serial No. 468,818

11 Claims. (Cl. 215—43)

The present invention relates to closure caps and more particularly to a screw cap having means adapted to minimize the breakage of glass containers in the application thereof.

5 One of the difficulties encountered in the use of screw caps, particularly with lug caps, is that the sealing strains upon the threads of the containers exceed the strength of the threads and cause the container to break. This is due to the 10 fact that the forces acting upon the thread are substantially in a vertical upwardly direction. In other words, the upward pressure of the lugs or threads of the cap against the threads on the container for holding the cap on the container 15 is directed against the outwardly extending portions of the threads which in turn is transmitted as a shearing or bending moment on the side-wall of the container.

It is customary to apply the caps to containers 20 by mechanical means, which are capable of sealing the containers very rapidly and more securely than by hand. Both the caps and containers vary in dimensions from a true standard. The present lug caps are not capable of yielding sufficiently to compensate for the necessary variations in all cases and imperfect seals and broken containers result. This is particularly true when an undersize cap is applied to an oversize container, or to a container having lugs or threads 25 too low on the neck thereof. To avoid this, the thickness and strength of the lugs or threads on the containers have been increased; however, the shearing moment caused by the unbalanced forces breaks the container at times, the glass 30 falling into the product. Such contingencies are costly because the entire package is impaired and it becomes necessary to slow up the operation of the sealing machines and, in some cases, to decrease the tightness of the seal. When the caps 35 are oversize, or when the container lugs are too high, the lugs of the cap have a tendency to ride under the threads and fail to seal the package.

Considerable difficulty is also encountered due 40 to the fact that the liners fall out of the caps in shipment. Attempts have been made to remedy this by increasing their size, but this causes the liners to buckle and impair the seal. Many of the caps do not center properly because of variations in size, which increases the tendency for 45 the lugs on the caps to ride over the threads on the container and causes an inefficient seal.

The present invention overcomes these difficulties by providing a cap construction which 50 minimizes the sealing strains upon the threads

and side wall of a container, properly centers the cap, permits the use of a larger liner, and also permits a greater range of variation from the standard size of container without impairing the seal or damaging the container.

An object of the invention is to minimize the sealing strains upon the threads and side wall of a container; and to provide effective means to overcome these strains.

Another object of the invention is to minimize 35 the breakage of the containers and the threads thereon occasioned by excessive strains applied thereto.

Another object of the invention is to reduce 40 the cost of sealed packages by providing a cap construction which can be readily applied without breaking the containers or parts thereof.

Another object of the invention is to prevent 45 liners from falling out of the caps, and to prevent their buckling during the sealing operation.

Another object of the invention is to provide a 50 cap which can be sealed to a container and which will compensate for variations in sizes without impairing the effectiveness of the seal.

Another object of the invention is to provide 55 a cap adapted to be sealed more securely onto containers to prevent the caps from being released accidentally.

Another object of the invention is to center the 60 cap with respect to the container to provide an efficient seal and to increase the permissible tolerance in the variation of the size of both the container and cap.

Another object of the invention is to provide a 65 cap adapted to form a double seal upon a container to minimize defective seals.

A further object of the invention is to provide 70 a cap having a resilient inclined annular portion in the cover portion thereof adapted to counter-balance the sealing forces of the cap upon the threads of a container.

Other and further objects of the invention will 75 be clear from an understanding of the description of the preferred embodiment, or will be indicated in the appended claims, and various advantages 80 not referred to herein will occur to one skilled in the art upon employment of the invention in practice.

A preferred embodiment of the invention has 85 been chosen for purposes of illustration and description and is shown in the accompanying drawing, wherein

Fig. 1 is a perspective view showing the closure applied to a container;

Fig. 2 is a side elevational view, partly in sec- 90

tion, showing the closure applied to a container;

Fig. 3 is a fragmentary enlarged sectional view illustrating the effective sealing forces of the closure upon a container;

5 Fig. 4 is a fragmentary vertical sectional view illustrating another application of the invention; and

10 Fig. 5 is a fragmentary sectional view illustrating the closure applied to a particular design of container.

15 Referring to the drawing, there is shown a closure cap having a cover portion 1 and a depending skirt 2, with its lower edge rolled to form a bead or wire edge 4. A series of lugs 5, shown herein as four in number, are formed from the wire edge and extend inwardly to engage a corresponding series of threads or ribs 7, preferably of the interrupted type, provided about the upper side wall 9 of the container. The skirt portion 20 of the cap is knurled or corrugated, as shown at 10, to facilitate application and removal thereof, and to enhance the appearance of the cap.

25 The cover portion 1 of the cap comprises an annular portion 11, adapted to extend over the rim 12 of the container, and a central depressed portion 14. The central portion 14 and the rim portion 11 are joined by an annular inclined or bevel portion. The purpose of the inclined band 15 will be described more fully hereinafter. A 30 suitable cardboard liner or gasket 16, usually a circular disc member, is disposed in the cover portion of the cap to provide an effective seal.

35 Heretofore, in the types of caps manufactured for screw containers, the gasket or liner would contact only with the top edge or rim of the container; since imperfections frequently occur at this portion of the container, the cap and gasket would fail frequently to seal the container properly. Attempts were made to correct this by forcing the cap more tightly upon the container. The 40 result was that the shearing forces exerted upon the lugs of the cap would break the threads of the container or would distort the lugs so that they would ride over the thread. These difficulties 45 are overcome in the present invention by the bevel portion 15 which holds the gasket against the inner edge of the mouth of the container and upon the rim thereof, and also affords a better seal with the same sealing effort, due to the combined 50 side and rim seal.

55 In the breakage of containers heretofore during the sealing operation, it has been noted that the containers consistently break, not always by shearing of the thread, but more often by a continuous break across the side wall of the container, as indicated by the dot and dash line 13, in Fig. 3. The break begins substantially at the bottom of the thread and proceeds in a zigzag direction upward and inwardly to a 60 point substantially below the inner side of the rim of the container. The annular inclined sealing zone 15 in the preferred embodiment of the cap presses outwardly upon the rim of the container in a direction indicated substantially by the arrow A which counteracts the force applied 65 by the lug of the cap in the general direction indicated by the arrow B. The pressure exerted upon the resilient annular inclined portion 15 substantially neutralizes the force created by the lug of the cap, thereby minimizing the resulting force which tends to break the container. The 70 inclined sealing surface, due to its resilience, serves the additional purpose of preventing the cap from becoming accidentally loosened in handling or otherwise.

75 It is customary to stamp the liners 16 from a continuous strip and insert them in the caps. A small percentage of the liners becomes dislodged, which, of course, is objectionable. Attempts have been made to enlarge the liners, but the large liners buckled, thereby impairing the sealing qualities of the cap. In the preferred embodiment, illustrated herein, the liners are preferably larger than the usual size so that when inserted in the caps, their outer periphery engages the inner wall of the skirt of the cap. When the caps are applied to the containers, the depressed center 14 bends the liner, which reduces its external dimension, pulling its outer periphery away from the skirt of the cap, so that when sealed there is a small clearance 21 between its edge and the skirt of the cap. In this way, the liner can be made large enough to stay within the cap without occasioning buckling during the sealing operation.

80 Considerable difficulty has also been encountered heretofore due to the fact that lug caps shift laterally with respect to containers. This causes the lugs to engage the threads on the container unevenly and increases the tendency for 85 the lugs to ride over the threads. The seal is also less effective due to the fact that one portion of the cap may be pulled down further than another. The annular inclined surface 15 of the present cap centers it with respect to the 90 container and prevents lateral shifting of the cap and the resulting disadvantages. In addition, the upward pressure on the inclined surface 15 tends to contract the lower edge of the skirt, thereby preventing the lugs from spreading and 95 minimizing the tendency for them to ride over the threads of the container.

100 A very secure seal is provided because the cap is properly centered and the skirt is pulled downward evenly in the application thereof. The inner part of the cap extends downwardly over the inner edge of the rim of the container, thereby producing, in effect, a secure double seal. The inclined portion 15 forms a seal on the inner 105 side of the rim and the lugs pull the skirt of the 110 cap downwardly to form a secure seal between the top of the rim of the container and the flat portion of the cover of the cap.

115 In Fig. 2, a cap in accordance with the present invention, is shown applied to a very small 120 bottle such as is used for prescriptions and the like. The construction of the cap is substantially the same as shown in Fig. 1 except that only two lugs are provided in the cap. The greatest difficulty in connection with breakage 125 is encountered with these smaller caps with two holding lugs. The same principles apply irrespective of the number of lugs, as described above, to center the cap, minimize the unbalanced forces and eliminate breakage.

130 The construction shown in Fig. 4 is slightly different and illustrates the use of an annular groove 19 formed in the cover part of the cap adjacent the inner side wall of the container. The outer incline of the groove presses outwardly against the rim of the container somewhat similar to the pressure applied by the bevel portion 15 in the construction, shown in Figs. 1 to 3. The double seal is formed, and the forces are balanced in the same manner as described hereinbefore. Certain 135 packers may object to the depression of the center of the cap purely because of personal dis- 140 taste. Such packers may be pleased by the construction shown in Fig. 4.

145 While the cap described herein is applicable to

standard containers, as illustrated in Figs. 1 to 4, it is shown applied to a particular design of container in Fig. 5. Preferably, the container is provided with a bevelled inner edge 18 adapted to co-
5 operate with the inclined annular surface 15 of the cap. The angular inclination of the bevelled surface 18 is preferably of an angle of about 10° and substantially the same as the angular inclination of the annular inclined surface 15 of the cap;
10 the inclination of these parts preferably being the same as the angular inclination of the top surface 19 of the cap lug and of the bottom surface 20 of the container thread. The thickness of the wall of the container may be determined accord-
15 ingly. In this construction, the portion of the container between the dotted lines 21 is under direct compression and any shearing action is eliminated or minimized. By so balancing the compression forces, breakage of the containers
20 is prevented.

Preferably, the caps and disc liners illustrated herein are manufactured and assembled and shipped in assembled state to packers. The caps are applied to the containers either by hand or
25 machinery, but generally by machinery in the larger packing plants. The operations may be carried out rapidly and neither the seal nor the container will be affected materially by excessive pressure which may be applied in the sealing op-
30 eration.

It will be seen that the present invention provides a very effective cap which can be manufactured at the same or less cost than caps manufactured heretofore. Breakage of the containers in
35 the application of the cap is minimized by counterbalancing the moment or force created by the lug of the cap pressing against the thread of the container. The invention also provides a double seal which is extremely effective. The inclined
40 annular portion 15, in addition to providing a double seal, centralizes the cap with respect to the container, prevents buckling of the liner during the sealing operation, and counterbalances the force exerted by the lug of the cap, thereby pre-
45 venting breakage. In addition, it permits a secure seal throughout a substantial range of vertical movement of the cap, causing the cap to seal with a minimum effort and preventing the cap from damaging the container when excessive effort is
50 applied in the sealing operation. It will of course be understood that the closure caps described herein may be constructed of any desirable material and that the invention is not limited to caps made of metal. The cap is rugged in con-
55 struction and fully capable of withstanding the rough usage to which it may be subjected.

As various changes may be made in the form, construction and arrangement of parts without departing from the spirit and scope of the invention, and without sacrificing its advantages, it is to be understood that all matter herein is to be interpreted as illustrative and not in a limiting sense.

Having thus described my invention, I claim:

- 60 1. A screw closure cap comprising a cover portion and a depending skirt having a bead at the lower edge of said skirt, lugs in said bead for engaging suitable spaced projections on a container, and an annular inclined band in said cover portion adapted to engage the inner side of the rim of the container and cooperate with said lugs to minimize unbalanced sealing strains upon the projections of the container when the cap is applied to the container.
- 65 2. A sealed package comprising a container having a plurality of spaced threads thereon, the lower surface thereof being angularly disposed to the side wall of said container, an inclined zone at the inner mouth portion of said container, and a cover cap comprising a skirt having thread engag-
70 ing means therein and a cover portion, an annular resilient inclined zone in said cover portion adapted to abut said zone at the inner mouth of the container, said lower thread portions and said inclined zones on said cap and container being substantially parallel to each other, thus causing the sealing forces between said cap and container to be resolved into a series of compressive forces perpendicular to said parallel members whereby vertical shearing forces against the thread and the container are eliminated and breakage thereof is prevented. 80
- 75 3. A sealed package comprising a container provided with interrupted threads extending circumferentially about the periphery of the container below the mouth thereof and substantially in the same horizontal plane, and a closure cap having a top portion and a depending skirt, a resilient annular bevelled portion in the top portion of the cap adapted to engage the inner periphery of the mouth of the container, a rolled bead at the lower edge of the skirt of the cap, and lugs formed in the bead adapted to cooperate with the bevelled portion to hold the cap resiliently upon the container to minimize the unbalanced sealing forces 90 exerted on the threads of the container. 95
- 80 4. A sealed package comprising a container provided with a plurality of threads adjacent to the mouth thereof of spaced endwise with respect to each other and a bevelled surface at the inner periphery of the mouth of the container, and a sheet metal closure cap having a top portion and a depending skirt, a resilient annular portion in the top of the cap adapted to engage the bevelled portion at the mouth of the container, a plurality of lugs formed in the lower edge of the skirt of the cap adapted to engage the threads of the container and to hold the cap resiliently upon the container, said cap being movable in an axial direction with respect to said container independ- 100 105 110
- 85 5. A sealed package comprising a container provided with a plurality of projections extending about the container adjacent to the mouth thereof, said projections being in substantially the same plan and being spaced endwise with respect to each other, and an inclined annular bevelled zone at the inner periphery of the mouth of the container, and a sheet metal closure cap having a top portion and a depending skirt with a beaded lower edge, a resilient annular bevelled portion in the top portion of the cap adapted to engage and abut the inclined bevelled zone of the container, and lugs formed from the lower beaded edge of the cap adapted to engage the projections on the 115 120 125 130 135 container, the lower engaging surface of the container projections being substantially parallel to the inclined bevelled surface at the inner mouth of the container, whereby the cap lugs and inclined zones cooperate to minimize the unbalanced sealing forces exerted upon the projections and the portions adjacent to the mouth of the container. 140
- 90 6. A sealed package comprising the combination of a container, having a plurality of inclined projections spaced endwise with respect to each other and being in substantially the same horizontal plane, said container having an annular bevelled zone at the inner side of the rim thereof, a closure cap having a cover portion and a de- 145 150

pendent skirt, the lower edge of said skirt being rolled outwardly into a bead and a plurality of lugs formed from said bead and spaced a substantial distance apart to cooperate with the projections on the container, the cover portion of said closure cap having an inclined zone adapted to cooperate with said bevelled zone on the container to minimize unbalanced forces on the container occasioned by the pressure applied by the lugs of the cap, and a liner interposed between the rim of said container and the cover portion of the cap.

7. A sealed package comprising the combination of a container having thread projections thereon, a sheet metal closure cap having a cover portion and a depending skirt, the lower edge of said closure cap being rolled outwardly into a bead, screw lugs separated a substantial distance from each other formed from said bead to engage the projections on the container to seal the cap upon the container, the cover portion of said cap having an inclined annular surface adapted to engage the inner side of the rim of the container to counteract the unbalanced forces created by the lugs of the cap in sealing the cap on a container.

8. In a sealed package, the combination of a container having projections thereon for engagement with the closure cap, the lower sides of said projections being at an angle of substantially 80° to the vertical axis of the container, the inner rim of said container having an annular bevelled zone likewise at an angle of substantially 80° to the vertical axis of the container, a closure cap having a cover portion and a depending skirt, the lower edge of the skirt of the cap being rolled outwardly into a bead, a plurality of lugs formed from said bead and separated a substantial distance from each other, said cover portion of the cap having an annular bevelled surface inclined about 10° to the cover portion adapted to cooperate with the annular bevelled surface of the container, the upper inner surface of the lugs of said cap being substantially parallel to said annular inclined surface in the cover portion whereby the parallel surfaces of said cap and said

container cooperate to minimize the unbalanced sealing forces and to prevent breakage at the upper end of the container.

9. A container having a substantially horizontal sealing surface at the rim thereof, an annular bevelled surface at the inner edge of said first surface forming an angle of about ten degrees therewith, a substantially vertical exterior side wall adjacent the rim, and a plurality of projections spaced endwise with respect to each other on said side wall of the container having an inclined lower surface forming an angle of about one hundred degrees with the side wall of the container, said bevelled surface and said lower inclined surface of the projections being substantially parallel with respect to each other, whereby sealing forces effective thereon are resolved into a series of compressive forces substantially perpendicular to said parallel surfaces, whereby vertical shearing forces are substantially eliminated to prevent breakage of the lug or container.

10. A screw closure cap comprising a cover portion and a depending skirt having a bead at the lower edge of the skirt, lugs in said bead for engaging suitable inclined spaced projections on a container, and an annular inclined zone in said cover portion extending inwardly and downwardly over the inner side of the rim of the container to cooperate with said lugs to minimize unbalanced sealing strains upon the projections of the container when the cap is screwed on a container.

11. A screw closure cap comprising a cover portion and a depending skirt having a bead at the lower edge of said skirt, lugs formed from said bead in the lower edge of said skirt for engaging suitable spaced projections on a container, a liner in said cap, and an annular groove in the cover portion of said skirt having its outer inclined portion adapted to press against the inner side of the rim of the container through the intermedium of said liner and cooperate with said lugs to minimize unbalanced sealing strains upon the projections of the container when the cap is screwed onto the container.
